UNITED STATES PATENT OFFICE.

FRANK P. DAY AND CHARLES C. HARTZOG, OF MONROE, LOUISIANA.

LUBRICATOR.

1,049,059.

Specification of Letters Patent.

Patented Dec. 31, 1912.

Application filed February 13, 1912. Serial No. 677,371.

To all whom it may concern:

Be it known that we, FRANK P. DAY and CHARLES C. HARTZOG, citizens of the United States of America, residing at Monroe, in the parish of Ouachita and State of Louisiana, have invented new and useful Improvements in Lubricators, of which the following is a specification.

Our present invention relates to improvements in lubricators or lubricating devices and has particular application to feeding attachments for engine lubricators.

In carrying out this invention, it is our purpose to provide an attachment of this character whereby the lubricant or lubricating oil may be fed from a reservoir or container to a battery of engines or the like in order to properly lubricate the same, water of condensation serving to float the oil in the reservoir or container and supply the same to the lubricator, preferably sight feed, thence to the cylinders of the engines or the like apparatus.

Furthermore, we aim to provide a lubricating device of this type wherein the lubricant may be fed to the engine cylinders irrespective of the filling of the reservoir. In other words, the invention involves a by-pass around the reservoir whereby the water of condensation may act upon the lubricant to supply the same to the engine cylinders when the reservoir supply has been cut off for filling purposes.

With the above and other objects in view, the invention consists in the construction, combination and arrangement of parts hereinafter set forth in and falling within the scope of the appended claims.

In the accompanying drawing, the figure 40 is a diagrammatic view showing certain of the parts in section.

Referring to the accompanying drawing in detail, a steam main is designated at 1 and as shown has communication with an engine cylinder 2 by way of a pipe 3 equipped with a controlling valve 4 so that communication between the steam main and the engine cylinder may be cut off when desired. Conveniently located with respect to the engine cylinder, is a lubricant reservoir or container 5 provided with the usual gage or sight glass 6 and equipped with a dome 7 in communication with the reservoir and closed by means of a filling plug or cap 8. Connected to the steam main 1 and in open communication therewith at an appropriate

distance from the pipe 3, is a condenser 9 having communication with the reservoir 5 by way of a pipe 10 equipped with a controlling valve 11 and designed to supply the water of condensation to the reservoir 5 so that the oil or other lubricant within such reservoir may be floated therein and driven into the dome 7. Arranged within the reservoir 5 and extending into the dome 65 7 is a lubricant conveying pipe 12 the exposed or free end of which is connected to an auxiliary multiple sight feed reservoir 13 so that in the floating of the oil within the reservoir, the former may be conveyed 70 to the lubricator 13, thence to the cylinders of the engine in a manner to be presently described. A valve 14 is located within the pipe 12 so that communication may be established between and cut off from the 75 container and lubricator when desired or necessary. The auxiliary reservoir 13 as shown is in open communication with a distributing main 15 provided with a plurality of sight feed lubricators 16, one of which is 80 connected to the pipe 3 of the engine cylinder 2 while the others are adapted for communication with other engines or the like apparatus so that a plurality of engines may be lubricated or oiled from a common source 85 of supply, thereby preventing waste of the lubricant and reducing the cost of lubrication to a minimum.

When the lubricant within the reservoir has been exhausted, and it is desired to refill the reservoir or container, the valves 11 and 14 are closed, and the water of condensation within the reservoir drained by way of a drain cock 17, subsequent to which action the filling plug is removed to facilitate the refilling of the reservoir.

Heretofore, in the construction of lubricators of this type, the lubricant supplied to the engine cylinders has been cut off in the filling of the reservoir, whereby the 100 engines have been obliged to operate without oil for a certain period of time. In order to overcome this objection and supply oil to the cylinders of the engine or other apparatus during the filling of the 105 oil container or reservoir, we have provided a by-pass around the container and in communication with the condenser and auxiliary reservoir so that when the container has been cut out of service, the residual 110 lubricant within the auxiliary reservoir may be forced into the engine cylinders,

2
said residual lubricant being usually sufficient to keep the cylinders oiled during the refilling or recharging of the reservoir. This by-pass as shown, includes a pipe 18 connected at one end to the pipe 10 immediately adjacent the juncture of the latter pipe with the condenser 9, and having its opposite end depending into the auxiliary reservoir 13, a suitable valve 19 being interposed between the ends of the pipe 18 so that the by-pass may be cut out in the normal operation of the oiler or lubricator.

From the above description taken in connection with the accompanying drawing, it will be seen that we have provided a lubricator for engines which may be operated at all times irrespective of the condition of the oil within the reservoir and whereby a plurality of engines or the like may be supplied with a lubricant from a single source of supply.

We claim:

1. In a lubricator, a steam main, a condenser in communication with said main, a lubricant container in communication with said condenser, an auxiliary reservoir in communication with said container and adapted to supply oil to an engine cylinder, and a by-pass around said container and designed to establish communication between said condenser and auxiliary reservoir whereby said auxiliary reservoir may be operated independently of the container.
2. In a device of the class described, a

steam main, a condenser in communication 35 with said main, a container in communication with the condenser, an auxiliary reservoir in communication with the container, a distributing main in communication with the auxiliary reservoir and adapted to supply a 40 lubricant to a plurality of engine cylinders; and a by-pass around said container and between said condenser and auxiliary reservoir whereby said auxiliary reservoir may be operated independently of the container. 45

3. In a lubricator, a steam main, a condenser in communication with said main, a lubricant container in communication with said condenser, an auxiliary reservoir, a 50 conduit connecting said auxiliary reservoir with said container, a by-pass around said container and designed to establish communication between said condenser and auxiliary reservoir whereby the auxiliary reservoir may be operated independently of the 55 container, and means in said conduit and by-pass and operable independently of each other to cut off communication between said container and auxiliary reservoir and the condenser and auxiliary reservoir. 60

In testimony whereof we affix our signatures in presence of two witnesses.

FRANK P. DAY.
